UNITED STATES PATENT OFFICE

UNITED STATES PATENT OFFICE

ROBERT FOSTER, OF CHICAGO, ILLINOIS, ASSIGNOR TO METAL TRAFFIC MARKER CORPORATION OF NEW YORK, N. Y., A CORPORATION OF NEW YORK.

TRAFFIC AND INDUSTRIAL MARKER

Application filed August 10, 1927. Serial No. 211,903.

100

The object of the invention is to provide improvements in surface markers, and particularly in those which are especially adapted for use on highways and in industrial plants, to designate locations, boundaries, areas, etc.

Another object is to provide a marker which can be secured to substantially any surface, including asphalt, concrete, wood, etc., and which will retain the glossy, polished, or light-reflecting surface with which it is originally provided, substantially regardless of local atmospheric conditions, or the presence of materials which normally tend to corrode metallic surfaces in general, such surface if desired being provided with a unitarily secured sheathing.

Still another object is to provide a marker having a disc-like head, provided with an annular recess into which the material of some surfaces such as asphalt can flow or creep, and with a pair of integral, oppositely positioned, tongue-shaped prongs extending from within said recess, and which are adapted when driven into a surface to spread in opposite directions, so that thereafter they co-operate to prevent the accidental loosening or dislodgment of the marker from the particular surface.

30 And a still further object is to provide the marker with a groove, positioned between said prongs and connecting the diametrical-
35 ly opposite marginal portions of the said an-
nular recess, whereby the actual connection
35 of each prong with the disc-like head is
spaced inwardly from the plane of the lower
or supporting face of said head, with the re-
sult that the flexing of each prong when
driven into a surface commences closer to
40 the head than would otherwise be the case,
and also with the result that no recess is
created in the normally upper or exposed
surface of the marker, due to shrinkage of
the metal when cooling, as is likely to occur
45 when forming the marker by casting.

The invention comprises further details of construction which are fully brought out in the following description, when read in conjunction with the accompanying drawings, in which Fig. 1 is a side elevation of one em-

Referring to the drawings, the improved marker adapted particularly for industrial and similar uses, comprises a disc head 1, having a normally upwardly or outwardly directed convex surface 2, which is buffed or otherwise polished, so as to provide an initial light-reflecting surface, and which surface when the marker is formed of Monel metal, ascoloy, stainless steel, or similar alloys, will permanently retain its original reflectivity without corrosion.

The under-surface 3, adjacent to the margin of the said head lies in a plane and is designed to support the marker upon the surface to which the latter is attached, and to likewise support the weight of any article which may rest upon, or pass over, the marker when in position. Coaxially with the periphery of said head, the marker is provided upon its under side with an annular groove 4, which surrounds a plurality of tongue-shaped spurs 5, the radially outer surfaces 6, of which form segments of a cylinder, while their adjacent surfaces 7, either diverge outwardly along curved paths, along straight paths, or are substantially parallel for a distance and thence diverge towards the respective pointed extremities 8. With any such shape, however, the act of driving the spurs into a given surface causes said prongs to flex or curve radially outwardly, substantially as shown in Fig. 4, tho not necessarily in all cases to such a wide angular relation.

While the spurs 5 may extend from the plane of the under surface of the marker's head, and close together at their bases, for several reasons it has been found advantageous to separate the spurs by a transversely extending groove 9, which connects the diametrically opposite portions of the annular groove 4. Thus, when driving the marker into relatively yielding material, such as asphalt and the like, that portion of said ma- 95 100

terial, which is displaced laterally by the upwardly increasing width of the spurs, "flows" into the grooves 4 and 9 and eliminates the tendency otherwise to prevent the under surface from reaching and resting uniformly upon the surface to which the marker is secured. Also, while only a pair of oppositely positioned prongs is illustrated, the invention provides for the use of any desired number, but preferably comprising oppositely positioned pairs, whether two, four, or more, in the aggregate.

As hereinbefore referred to, the present marker, instead of being made of a single part, such as a metal casting with its normally exposed surface polished, may be provided with a separate sheathing of Monel-metal, ascoloy, or similar non-corrosive metal, unitarily secured to such exposed surface in any desired manner, as in the case of a co-pending application, of which as regards this detail this application is a continuation. Such a sheathing 2^a is shown in Fig. 5, and is secured unitarily to the head of the marker as by crimping or otherwise bending the marginal portion 2^b about the periphery of the head 1.

Having thus described my invention, what I claim and desire to protect by Letters Patent of the United States is:—

1. A surface marker, comprising a head, having a pair of spaced integral prongs extending from the normal underside and spaced from the edges of said head, and separated by a groove adapted to receive material displaced by said prongs when driven into a surface, the transverse extent of said prongs at their union with said head being less than the width of said head.

2. A surface marker, comprising a head, having a pair of spaced integral prongs extending from one side, a groove in said head surrounding said prongs and closely adjacent thereto, and a second groove extending between said prongs and above the plane of the normal under side of said head, said grooves being adapted to receive material displaced by said prongs when driven into a surface.

3. A surface marker, comprising a head, having a pair of spaced integral prongs extending from one side and spaced from the edge of said head, and separated by a groove which extends into the adjacent surface of said head, and is adapted to receive material displaced by said prongs when driven into a surface.

4. A surface marker adapted to be driven into the material of a paved surface and comprising a convex head of greater height at its center than at its periphery above the plane of its under surface, and a downwardly depending means formed integral with and spaced from the periphery of said head for fastening said head in a predetermined po-

sition in such material, said fastening means comprising two prongs, initially spaced apart from their union with said head to their end portions, and capable of being further forced apart to form an anchor in said material, the point of joining of said prongs with said head being substantially near the transverse center of said head between said under surface plane and the point of maximum height above said plane.

In testimony whereof I have affixed my signature.

ROBERT FOSTER.
